FIG. 1 is a side elevation of the shield for electrical plug prongs of this invention.

FIG. 2 is a right end view of the plug block of FIG. 1.

FIG. 3 is a top plan view thereof.

FIG. 4 is a bottom plan view thereof.

The shield fits over the prongs of an electric plug so that when said prongs are inserted into the side apertures of the shield (FIG. 2), the retaining pin (the handle of which is best seen in FIGS. 1 and 2) penetrates the shield and extends through the apertures in said prongs, thus fixing the prongs within the shield.

I claim:

The ornamental design for a shield for electrical plug prongs, as shown and described.
